UNITED STATES PATENT OFFICE.

WALTER L. BETTS, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRIC SWITCH.

Application filed August 5, 1924. Serial No. 730,157.

This invention relates to radio control switches, for use in apartment houses, hotels and the like, for associating the receiving apparatus with the aerial and ground wires and for varying the volume of current received therefrom for actuating the receiver set in order to operate a loud speaker at different degrees of loudness, as high, medium or low, or to reduce the volume sufficiently to operate an ordinary head set when it is not desired or convenient to have the loud speaker operating.

The invention consists of a switch in unit form designed to go into standard outlet boxes and arranged to take standard switch flush plates such as are used in electric light push button switches, whereby these units may be readily installed in the walls of the apartment or hotel rooms and be flush with

20 the walls and out of the way.

Other features of invention and advantages will appear from the following description and the claim appended thereto, reference being had to the accompanying drawings in which Fig. 1 is a front view of the unitary switching device with the supporting plates partially cut away. Fig. 2 is a side view thereof. Fig. 3 is a diagrammatic view of the circuit used in said device. Fig. 4 is a side assembly view of the switching structure modified showing the flush plate and outlet box in sections. Fig. 5 is a back view thereof and Fig. 6 is a diagrammatic view of the circuit used in connection with the modified switching device shown in Fig. 4.

The switching device shown in Fig. 1 consists of a supporting insulating plate 11 which is mounted and held securely in an outlet box 9 of a standard type adapted to hold the flush plate 10 in adjusted positions, by means of a number of screws 12. On the plate 11 is mounted a switching device which generally consists of an insulating plate 13 held in spaced relation with reference to the plate 11 by means of posts 14, 15 and 16. In plate 13 there is mounted a sleeve or bearing 17 in which the shaft 18 rotates. This shaft extends from each side of the sleeve 17 and on its ends are secured a knob 19 and a wiper 20 which is adapted to contact with a plurality of arcuately disposed contact points 21, 22, 23 and 24 embedded in the plate 13. Each of these contacts extends a small distance on the opposite side of the

plate 13 for attaching their respectively associated wire terminals 25, 26, and 27 shown in the diagrammatical view of Fig. 3.

It is to be noted that the contact point 23 does not form a part of the sound reproducer 60 operating circuit but is provided only for holding the wiper 20 in neutral position.

The resistances 28 and 29 shown in Fig. 3 are wound on a spool 30 which is held on the plate 13 by any suitable means.

A spring 31 secured on the plate 13 contacts with the inwardly extending end portion of the shaft 18 which cooperates with the contacts 21, 22 and 24 for completing the telephone circuit in the order indicated by 70 the symbols H, M, L, OFF, shown in Figs. 1 and 3 and which indicate the condition of the circuit for high, medium, low and no tone respectively.

Brackets 32 and 33 are secured to the plate 75 11 and are each provided with screws 34 and 35 for securing the terminals of each incoming wire (not shown) to the switch. On the plate 11 is mounted a spring 37 and associated sleeve 36 which may be of any well 80 known type and in which the plug of the head set cord or loud speaker may be inserted for connection.

The modified switch unit shown in Fig. 4 generally consists of a mounting plate 11 85 in which the sleeves 35 and 36 are secured and to which the telephone head set or a loud speaker may be connected through the insertion of their respectively associated plugs 39 and 40 shown in the diagrammatic 90 view of Fig. 6. The conducting strip 48 is provided for electrically connecting the sleeves 35 and 36 and for reenforcing the plate 11.

A resistance 41 which may be of any well 95 known type is provided in the operating circuit and is adapted for reducing the current to a volume suitable for reception in a telephone head set, the current being normally strong enough to operate a loud 100 speaker. This resistance is disposed between the resilient brackets 44 and 45 secured on the plate 11 which are provided with centering holes in which the metallic pointed end portions 46 and 47 of the resistance engage 105 as shown in Fig. 4. The screws 60 and 61 on strip 48 and spring 49 are provided for attaching the terminals of the incoming wires 50 and 51 respectively. The wire 52 has one end attached to the fastening por- 110

tion of spring 49 and the other end to the resilient bracket 44 in contact with the resistance 41 which in turn contacts with supporting bracket 45 in contact with the spring 53.

In the operation of the device shown in Fig. 1 and referring more particularly to its operating circuit shown diagrammatically in Fig. 3 the wiper 20 is shown resting on contact 21. In this position a circuit is closed through the side 25 of the incoming line whose terminal is connected to contact 21, the wiper 20 and the returning side 38 of the incoming line including resistance 28. Therefore, no current flows through the sound reproducer circuit and this circuit condition is indicated by the word "Off" printed on the face of the dial 10 in registry with the arrow 39 carried by the knob 19. When wiper 20 is moved on contact 22 a circuit for the receiver is closed through the side 25 of the incoming line, spring 37 the receiver loop and the returning side 38 of the incoming line through resistance 28. A very small amount of current flows through this circuit due to the resistance 29 bridged across the lines 25 and 38. The energy of the current flowing in the line circuit is sufficient for operating an ordinary telephone receiver or a receiver of the loud speaker sort at a low tone and this circuit condition is indicated by the symbol L disposed in registry with the arrow 39. When wiper 20 is moved in position at the points indicated by the symbol M a circuit is closed to the receiver through the side 38 of the line, resistance 28, sleeve 36, receiver loop, spring 37 and the returning side 25 of the line. The current flowing through the resistance 28, however, is sufficient to operate a loud speaker at a medium tone and this circuit condition is indicated by the symbol

M. When wiper 20 is moved on contact 24 a circuit is closed for the receiver through the side 25 of the line, spring 37, receiver loop, sleeve 36, wiper 20, contact 24, conductor 27 to the returning side 38 of the line.

The wiper 20 in position on contact 24 shunts the resistance 28 from the line circuit, and the current flowing in the operating circuit operates the loud speaker at a very high tone. The condition of this circuit is indicated by the symbol H in registry with the arrow 39.

In the circuit shown in Fig. 6 when a receiver of the loud speaker sort is connected to sleeve 35 a circuit is completed through the side 51 of the incoming line, loud speaker loop, spring 49, the strip 48 and the returning side 50 of the line. When the plug 60 of the telephone head set is inserted in sleeve 36 a circuit, is closed through the side 51 of the line, conductor 62, the telephone loop the spring 53, resistance 41 and the returning side 50 of the incoming line. The resistance 41 is made of such a value that the head set operates in a manner very similar to an ordinary telephone receiver.

What is claimed is:

In combination, an outlet box, a mounting plate fitting into said box, a resistance device carried on the back of the mounting plate having taps leading to contact points on said mounting plate, a wiper carried by said mounting plate for engaging said contact points, a flush plate, means for securing said mounting plate and flush plate to said box, and a jack carried by said mounting plate and extending through the flush plate.

In witness whereof, I hereunto subscribe my name this 29th day of July A. D., 1924.

WALTER L. BETTS.
